UNITED STATES PATENT OFFICE.

ROBERT GRAHAM WOODWARD, OF ALAMEDA, CALIFORNIA.

DESIGN FOR A BICYCLE-CARRIER.

SPECIFICATION forming part of Design No. 28,153, dated January 11, 1898.

Application filed October 12, 1897. Serial No. 654,999. Term of patent 14 years.

To all whom it may concern:

Be it known that I, ROBERT GRAHAM WOODWARD, of Alameda, in the county of Alameda and State of California, have invented and 5 produced a new and original Design for a Bicycle-Carrier, of which the following is a full, clear, and exact description.

Reference is to be had to the accompanying drawing, of which the figure is a perspective 10 view of a bicycle-carrier showing my design.

The leading feature of the design consists of the spaced hooks A and B, projecting in an upward direction, the base portions A' and B' being convergent and merging into the 15 broad forward continuation C of the bracket

D, the base portions A' B' of the hooks dipping from the bracket to the point of upward trend, the hooks rising suddenly from the base portion approximately at right angles thereto and rising to a height pronouncedly 20 in excess to the short dipped base portions which merge into the broad bracket D'.

I claim—

The design for a bicycle-carrier as herein shown and described.

ROBERT GRAHAM WOODWARD.
